ZINC DISTILLATION PLANT

Walter Malkomes, Essen, Germany, assignor, by
mesne assignments, to The Koppers Company
of Delaware, Pittsburgh, Pa., a corporation of
Delaware

Application June 13, 1931, Serial No. 544,245
In Germany May 14, 1930

6 Claims. (Cl. 75—28)

The invention relates to a process and for the recovery of zinc from zinc oxide, ores containing zinc oxide or similar material in which briquettes are first made from the zinc oxide containing material and coal, and are then hardened by coking of the coal and finally are brought, preferably in a continuous vertical retort oven, to the temperature required for the reduction of the zinc oxide and for the distillation of the metallic zinc.

10 In case of the well-known similar processes and apparatus, the coking of the zinc ore coal briquettes is effected in retorts heated from the outside, in which cases the heating up of these 15 retorts by the combustion of producer gas or by similar means is carried out.

Now, the object of the present invention is a process for the recovery of zinc from zinc oxide and similar materials in which first of all briquettes are made out of zinc oxide and coal, and 20 which, for the purpose of coking, are brought into direct contact with the distillation gases resulting from the reduction of the zinc oxide and after said gases have been freed from zinc and have been raised to the necessary temperature 25 required for the coking by previous partial combustion. According to this invention preferably, for this purpose, the gases serving to heat up the zinc oxide-coal-briquettes are passed, in countercurrent to the briquettes, supplied continually 30 or intermittently, through the shaft furnace used for the coking of the briquettes. Furthermore, according to this invention, all the gases leaving the coking ovens, after having been freed from the dust, tar- and hydro-chloric vapours, are utilized 35 for the preferably indirect heating up of the retorts of the coking oven. According to this invention, the gases are, previous to their further combustion in the heating flues of the reduction oven, led through a washer filled with 40 limestone and sprayed from above with water for the purpose of removing the hydrochloric vapours.

The process according to this invention above 45 all offers the important advantage, that the apparatus for the coking of the zinc oxide-coal briquettes can be made considerably smaller and cheaper than shaft furnaces serving for the coking, which have been customary up to the present 50 and which are heated from outside. Moreover, in the case of the process of this invention, the otherwise necessary producer gas employed for the heating of the coking oven is dispensed with.

An additional advantage of the process according 55 to this invention lies in the fact that any zinc

dust not completely separated out of the gases escaping the reduction oven in the usual zinc vapour condenser is, in consequence of passing of the gases through the coking shaft furnaces, precipitated during the coking process on the 60 surface of the zinc coal briquettes, which become plastic when heated so that the special removal of the zinc dust (necessary up to the present) from the waste gases of the reduction can be done away with.

65 On the drawing there is shown a vertical section of the apparatus serving to carry out the process in accordance with the invention.

In the apparatus shown on the drawing, a shaft furnace 1 is made use of for coking the zinc ore 70 coal briquettes made in a briquette plate not indicated, said furnace 1 being provided above with a charging hole 4 which can be closed by means of the cover 3 movable to and fro by the hand lever 2. The lower discharging opening 5 of the 75 coking shaft furnace is closed by the slide 6, which can be manipulated by means of a lever 7. Underneath the coking shaft 1 there is the heating chamber 8 of the reduction oven, the charging shaft 9 of which is connected up with the slide 6 80 and same can be closed by means of the slide. The heating chamber 8 is provided with the usual discharging appliance 10 with a run-off hopper 11, which delivers the material freed from the zinc and drawn off continuously from the reduc- 85 tion oven to the lorries 12.

The heating of the reduction chamber 8 is effected extraneously by the gases, which are burnt in the customary heating flues 13 provided for in the walls of the reduction chamber 8. The 90 heating flues 13 are each connected with cross-channels 14 and 15, which serve in alternation to supply the air for the combustion and to exhaust combustion products and the heating flues 13 are also in connection with channels 16 and 95 17 which supply the fuel gas for combustion.

The air supply channels 14 and 15 are connect- 100 ed up to the upper end of the regenerators 18, 19, respectively, which are arranged above one an- other along one side of the battery of reduction chambers 8 and heating flues 13. The regenera- 105 tors are as usual fitted with refractory bricks forming chequer work and underneath each is provided with a bottom channel 21, 22. Each of the regenerators 18 are in connection with the usual regenerator box 25 by pipe lines 23, and each of the regenerators 19 are in connection with a similar regenerator box 25' by the pipe lines 24; and each of the boxes 25, 25', are connected by 110

- pipe line 26 with a waste gas flue 27 that leads to a stack as is usual with regenerators.
- As is customary the regenerator boxes 25, 25' are each provided with an air door 28 which are opened at times and allow entry of air into the pipes 23, 24, and thence to the regenerators 18, 19. Further, a valve is provided in each regenerator box for controlling the flow of waste gas therethrough to the pipes 26. When the air door 28 for a regenerator box is open the waste gas valve is closed, and when the waste gas valve is open the air valve 28 is closed. The air and waste gas valves for the regenerators 18 operate in alternation with the similar valves for the regenerators 19.
- The horizontal connection channels 16 and 17, that supply the fuel gas to the flues 13 are connected up by means of a three-way cock 29 with a gas supply line 31.
- 20 The combustion of the fuel gas in the heating flues 13 of the reduction chamber 8 is effected upwardly and then downwardly in alternation in the flues 13. For this purpose the three-way cock 29 and the valves in the boxes 25, 25', are periodically reversed (about every thirty minutes) so that in one thirty-minute period air and combustible gas are fed into the lower ends of the heating flues 13 and in the next thirty-minute period air and combustible gas are fed into the upper ends of the flues 13. During such upflow combustion, the air valve 28 is open and the waste gas valve is closed for the regenerator boxes 25 of regenerators 19, and the waste gases pass from the horizontal flues 14 into the regenerators 18 thence to their respective regenerator boxes 25' and out through the pipes 26, the waste gas valve being open and the air valve 28 for the boxes 25' being closed. Upon reversal the air valve 28 is open and the waste gas valve is closed for the boxes 25'. Air then flows in through regenerators 18 thence into the horizontal flues 14, meeting fuel gas, from the conduit 16, in the top of the vertical flues 13, burns downwardly therein, and the waste gas passes out through the horizontal flues 5 to the regenerators 19 and their respective boxes 25 and thence to the pipes 26, the air valves 28 being closed and the waste gas valves being open for the boxes 25.
- The gases and vapours containing zinc which escape on the heating up of the carbonized zinc ore-coal briquettes are drawn off at the upper end of the reduction chamber 8 by the channel 32 leading out of the reduction chamber 8 and carried off to a condenser 33 in which the zinc vapours separate out in the form of liquid zinc metal, which can be drawn off by the opening 34 of the condenser 33 continuously or intermittently into a lorry 35 run in front of the condenser 33.
- 60 The vapours and gases which are not precipitated in the condenser 33 go forward through the pipe line 36 into a combustion chamber 37, where they are mixed with a certain quantity of air supplied by the pipe line 49, so that a part of the burnable gases entering the combustion chamber 37 is burnt, thereby heating up the total quantity of gas. The gases heated up in the combustion chamber 37 are conducted then through the pipe line 38 to the coking shaft furnace 1. They stream through the charge in the coking shaft 1 in countercurrent to the movement of same and are led off from the coking shaft through the pipe line 39 to a dust precipitating means 40 which is provided with horizontal intermediary floors 41 for picking up of the dust
- carried along with the gases. From the contrivance 40 the gases arrive then through the pipe line 30 to a recuperator 42 in which the hot gases serve to heat up the walls on the other side of which air is led for the purpose of being warmed up which then goes forward through the pipe line 49 to the preliminary combustion contrivance 37. The gas spaces of the recuperator 42 are connected by means of the pipe line 43 with the washing tower 44 which is packed with large grained limestone 45 and which is sprayed with water from the top by means of the distributing contrivance 46. The washing water is drawn off through the pipe line 47 at the foot of the washer 44 and returned to the distributing contrivance 46 by the pump 48 whilst a portion of the spent washing water is removed continuously or intermittently and replaced by clean water.
- At the upper end of the washer 44, there is connected up the gas pipe line 31, which serves to supply the gases to the valve 29 for delivery to horizontal channels 16, 17 of the reduction chamber.
- The invention as hereinabove set forth is embodied in a particular form of construction, but may be variously embodied within the scope of the claims hereinafter made.
- I claim:
1. A process for the recovery of zinc from oxidized zinc ores and the like and coal comprising, heating up and coking briquettes of the aforesaid materials by bringing the same in direct contact with the hot reduction gases from the following reduction step and heating and coking 105 said briquettes by the sensible heat of said reduction gases while hot from the reduction step, and then separately subjecting said coked briquettes to further extraneous combustion heating and thereby reducing the oxidized zinc compounds and driving off zinc vapours from the briquettes.
  2. A process for the recovery of zinc from oxidized zinc ores and the like and coal, which comprises: heating up and coking briquettes of 120 the aforesaid material; separately heating by extraneous combustion of gas the so coked briquettes to a temperature at which the oxidized zinc compounds are reduced and the zinc vapours driven off from the briquettes; effecting partial 125 combustion of the reduction gases from said reduction step and thereby further heating the same; bringing the latter gases into direct contact with the briquettes to be heated and coked and effecting the aforesaid heating and coking step with the sensible heat from the reduction step and from said partial combustion; and subjecting the briquettes from the aforesaid heating and coking step to the aforesaid reduction step.
  3. A process for the recovery of zinc from oxidized zinc ores and the like and coal, which comprises: heating up and coking briquettes of the aforesaid material; separately heating by extraneous combustion of gas the so coked briquettes to a temperature at which the oxidized zinc compounds are reduced and the zinc vapours driven off from the briquettes; effecting partial combustion of the reduction gases from said reduction step and thereby further heating the same; bringing the latter gases into direct contact with the briquettes to be heated and coked and effecting the aforesaid heating and coking step with the sensible heat from the reduction step and from said partial combustion; subjecting the briquettes from the aforesaid heating and coking step 135

to the aforesaid reduction; and preheating the air for said partial combustion step by heat exchange with the spent gas from said heating and coking step.

5 4. A process for the recovery of zinc from oxidized zinc ores and the like and coal, which comprises: heating up and coking briquettes of the aforesaid material; separately heating by extraneous combustion of gas the so coked briquettes to a temperature at which the oxidized zinc compounds are reduced and zinc vapours driven off from the briquettes; bringing reduction gases from said reduction step while hot into direct contact with the briquettes to be heated and coked and heating and coking said briquettes by the sensible heat of said reduction gases while hot from the reduction step; passing spent reduction gases from said heating and coking step to said reduction step and effecting the heating of said reduction step by extraneous combustion of said spent

5. A process for the recovery of zinc from oxidized zinc ores and the like and coal, which comprises: heating up and coking briquettes of the aforesaid materials; separately heating the so coked briquettes to a temperature at which the oxidized zinc compounds are reduced and zinc vapours driven off from the briquettes; bringing reduction gases from said reduction step while hot into direct contact with the briquettes to be heated and coked and effecting the aforesaid heating and coking step with the sensible heat from the reduction step and from the partial combustion; preheating the air for the partial combustion by heat exchange with spent gases from the heating and coking step; cleaning the spent heating gases from said heating and coking step and thereby freeing them from dust, tar and hydrochloric acid; passing the so cleaned gases to said reduction step, and effecting the heating of the reduction step by extraneous combustion of said cleaned gases with air regeneratively preheated by the heat from the combustion products of said cleaned gases.
